ABSTRACT OF THE DISCLOSURE

Two lengths of metal-sheathed explosive-detonating cord are placed on an aluminum plate in side by side position to form a double length portion of cord intermediate their ends. One end of each length of cord is secured to a body of explosive for initiation in response to detonation of the body. A detonator, attached to the body near one of the secured cord ends, detonates the body which initiates the cord lengths. Initiation fronts, travelling along the cord length, form offset or lateral marks in the aluminum plate where the fronts meet. The mark location relative to the cord lengths, detonation velocity of the cords and the distance between the secured ends enables a very accurate determination of the detonation velocity of the explosive body.

The invention described herein may be manufactured, used, and licensed by or for the Government for govern-
mental purposes without the payment to me of any royal-
ty thereon.

The conduct of research and development in the ord-
nance art has generated an ever increasing demand for
accurate and inexpensive devices for measuring the det-
onation velocity in explosives bodies. At present, me-
chanical and electronic devices are used, however, they
possess certain disadvantages in that, the mechanical de-
vices are slow and extremely complicated, and the elec-
tronic devices, although accurate, involve complicated
wiring and elaborate instrumentation and cannot there-
fore be used effectively in field operations. A relatively
inexpensive method, known in the art as the d'Autriche
method, has been used with some degree of success. This
method, which is an explosive-computational technique,
does not possess the accuracy of either of the aforemen-
tioned devices and is limited to relatively large bodies of
explosives.

It is an object of the invention to provide an inex-
pensive arrangement for very accurately measuring the det-
onation velocity of explosive bodies.

Another object of the invention is to provide such an
arrangement for determining the velocity of detonation
of relatively small explosive bodies without the need for
elaborate instrumentation or complex wiring.

Other objects, features and advantages will become ap-
parent from the following specification taken in conjunc-
tion with the accompanying drawings in which:

FIG. 1 is a schematic diagram of an apparatus for
measuring detonation velocities of explosives which em-
bodies principles of the invention.

FIG. 2 is a top plan view of the deformed surface plate
after the explosive body has been detonated.

An explosive body 10 (FIG. 1), having an unknown
detonation velocity, is provided with a detonator or elec-
trical blasting cap 11 which is connected thereto at one
end. Detonator 11 is preferably electrically actuated by
means of circuit 12 which includes a source of electrical
energy 13 and electrical switch 14. Other types of det-
onators may be used, however, with equal facility. Two
lengths of explosive-detonating cord 15 and 16 are cut
from a longer length of mild detonating cord (MDC) hav-

ing a flexible lead or other metal sheath around a core
comprising at least 0.5 and less than 2.5 grains per foot
of PETN explosive. Cord lengths 15 and 16 are placed
on a surface of aluminum plate 17 in side by side forma-
tion with substantially common right angular bends to
form a double length cord portion intermediate their re-
spective ends A and B. MDC cord lengths 15 and 16 ex-
tend substantially in a single plane at the plate surface
and should be equal to each other. When placed in for-
mation, the corresponding ends A and B should be equi-
distant from the respective right angle bends 18A, 18B.
The double length or overlapping portion of cord lengths
15 and 16 may be sprayed or otherwise coated with a
suitable adhesive resin to form a unitary cord length. The
plate 17 is preferably formed from a ductile or easily
deformed material such as aluminum, and an indicia mark
18 is formed on the plate at a location which is mid-point
between the right angle bends 18A, 18B of the double
length cord portion.

End A of MDC cord length 15 is operatively connected
to explosive body 10 at a point in close proximity with
detonator 11. Various connecting devices are available
which would facilitate this connection; however, whatever
mechanism is used, it is imperative that end A be so con-
nected to body 10 as to be initiated in response to the
detonation of the body. Cord 16 has an end B which is
connected to explosive body 10 in a manner similar to
that used in conjunction with end A of cord length 15.
The distance between points A and B in explosive body
10 is then measured and recorded for use in subsequent
computations.

The operation of the apparatus will now be described.
Circuit 12 is completed by closing switch 14 and electrical
energy from power supply 13 activates detonator 11.

Detonator 11 initiates detonation in explosive body 10
and produces a detonation wave front therein which pro-
ceeds along body 10 through points A and B. When the
detonation wave front reaches point A it will produce an
initiation front in MDC cord length 15. When the det-
onation wave front in body 10 reaches point B it will also
establish an initiation front in body length 16. These
initiation fronts will travel toward each other around their
rectangular formation. As each wave front proceeds along
the double length or overlapping cord portion, reaction
gases serve to destroy or remove the adjacent overlapping
cord portion without initiating it. When the two initia-
tion fronts meet, an indentation or mark 19 (FIG. 2) will
be formed in the surface of plate 17. Indentation 19 will
generally take the form of a double groove defined by
offset or lateral marks that terminate the respective single
grooves 20, 21 that are formed in or cut into the surface
of plate 17 by corresponding initiation fronts.

The distance L_{cm} along plate groove 20 from mid-point
indicia 18 to the double indentation mark 19 is measured,
and is equal to one-half the difference in initiated lengths,

$$\frac{L_{ma} - L_{mb}}{2}$$

of the cords 15, 16. Where D_e is the unknown detonation
velocity of the explosive body 10 having a measured dis-
tance L_{ab} between points A and B thereon, D_e is the
known detonating velocity of mild detonating cords 15
and 16, and L_{ma} and L_{mb} are the corresponding cord dis-
tances from mark 19 to respective ends A and B, D_e can
be evaluated from the following:

$$D_e = \frac{L_{ab} D_e}{L_{ma} - L_{mb}} \text{ or } \frac{L_{ab} D_e}{2 L_{cm}}$$

I wish it to be understood that I do not desire to be
limited to the exact details of construction shown and
described, for obvious modifications will occur to a per-
son skilled in the art.

I claim:

1. An apparatus for measuring the detonation velocity of an explosive body comprising,
    - a flat surface for supporting lengths of preselected metal-sheathed explosive-detonating cord, said surface being composed of a material that is marked by detonation of the cord,
    - a first length of metal-sheathed explosive-detonating cord having one end thereof securable to said explosive body for initiation in response to detonation of said explosive body, said first length extending outwardly of said explosive body and having a substantial portion positioned on said surface,
    - a second length of explosive-detonating cord having a substantial portion positioned on said surface abutting said first length portion to form a double length portion of said cord, said second length also having one end thereof securable to said explosive body a predetermined spaced distance from said first length securable end for initiation in response to detonation of said explosive body, and
    - means for detonating said explosive body adjacent said first length securable end,
- so constructed and arranged that said explosive body initiates said first length upon detonation of said

explosive body and said second length subsequent thereto, each of said initiated lengths having an initiation front which travels therealong to form a mark in said surface where said initiation fronts meet, such that said mark will have a location relative to said cord lengths and said predetermined spaced distance between said securable ends which is representative of detonation velocity.

2. The apparatus of claim 1 in which said surface is an aluminum plate, and said cord lengths extend in a single plane.

3. The apparatus of claim 2 wherein said plate surface has indicia means thereon located substantially at the mid-length of said cord double length portion.

4. The apparatus of claim 1 wherein said cord lengths are formed from mild detonating cord having an explosive core with a flexible lead sheath, said core comprising at least 0.5 and less than 2.5 grains per foot of PETN explosive.
